UNITED STATES PATENT OFFICE.

ALVA H. KIRK AND DONALD H. KIRK, OF MINNEAPOLIS, MINNESOTA.

STOP-SIGNAL FOR CARS.

1,262,675.

Specification of Letters Patent. Patented Apr. 16, 1918.

Application filed January 24, 1916. Serial No. 73,782.

To all whom it may concern:

Be it known that we, ALVA H. KIRK and DONALD H. KIRK, citizens of the United States, residing at Minneapolis, in the county 5 of Hennepin and State of Minnesota, have invented certain new and useful Improvements in Stop-Signals for Cars; and we do hereby declare the following to be a full, clear, and exact description of the invention, such as will enable others skilled in the art to which it appertains to make and use the same.

This invention has for its object to provide an extremely simple and highly efficient 15 stop signal for street cars; and to such ends, generally stated, the invention consists of the novel devices and combinations of devices hereinafter described and defined in the claims.

20 The signal device itself involves novel features, but the invention consists further in a novel co-operative connection between the same and the gate actuating device of the car. It is now the common practice to equip 25 street cars with stop signals, including electrically actuated bells and circuits with push buttons properly distributed throughout the car. With such systems, when the travel is heavy, and a good many people desire to get off at the same street, it frequently happens that the bell will be kept 30 ringing most of the time, which is not only objectionably noisy but uses up an unnecessary amount of current.

35 The present invention provides a visual stop indicator, either with or without a bell, and an arrangement wherein the signal device is actuated by first closing of the circuit produced by the first pressing of a 40 button, so that repeated pressing of the same or other buttons will not again close the circuit and will have no further effect on the set signal.

In the accompanying drawings which 45 illustrate the invention, like characters indicate like parts throughout the several views.

Referring to the drawings:

Figure 1 is a horizontal section with some 50 parts broken away, showing the improved stop signal applied to a street car and connected to gate actuating mechanism of the character disclosed in U. S. Patent 546,116, granted to Willard J. Hield, of date, September 10th, 1895, and entitled "Street car gate";

Fig. 2 is a plan view showing in detail the operating connection between the stop signal and gate actuating crank;

Fig. 3 is a view partly in elevation and 60 partly in vertical section showing the gate actuating crank post and the stop signal device;

Fig. 4 is a front elevation of the stop signal; 65

Fig. 5 is a similar view to Fig. 4, but with some parts broken away;

Figs. 6 and 7 are views in rear elevation showing the stop signal with the rear plate 70 of the case removed and with some parts broken away; and

Fig. 8 is a diagrammatic view showing the wires of the electrical connections.

The numeral 1 indicates the main compartment, the numeral 2 the front end vestibule, and the numeral 3 the rear end vestibule of an inclosed passenger car such as used on street railways and interurban systems. The numeral 4 indicates hinged gates 75 for opening and closing the entrance to the rear end vestibule 3. The hanger rods of these gates are provided, below the steps 5 with arms 6 that are connected by a link 7, the front end of the said link being connected to a long operating rod 8. The operating rod 8 extends below the floor of the car body and is connected to arms 9 of a crank rod 10 that is journaled in suitable bearings 11 on the front end vestibule 2 and is provided at its upper end with an operating hand crank 12 shown as applied in Figs. 1 and 2, but being removed in Fig. 3. This gate actuating device is that disclosed in the above noted Hield patent, and for the purposes of this case, it is only 95 necessary to state that when the crank 12 is turned to the position shown in Fig. 1, the gates will be opened and when the said crank is given approximately one-half rotation, will close the gates and throw the 100 arms 9 and operating rod 8 into a dead center relation so that the gates will then be locked.

For applying the stop signal to a car of the above character, the box casing 13 thereof is suitably secured within the front end vestibule 2 in position where it will be in front of the motorman. The front plate of the casing is preferably removable and it is formed with a horizontal slot 14 through 105 which the stop signal may be readily seen by the motorman. Mounted within the cas-

ing 13 and held for vertical sliding movements by a suitable guide casing 15, is a thin flat indicator plate 16, preferably made of sheet metal. On the face of this indicator plate 16 is printed, painted, or otherwise marked, the word "Stop", which will be exhibited through the opening 14, when, and only when, the signal plate is dropped.

Secured to a supporting lug 17 on the 10 guide casing 15 is an electro-magnet 18 that acts upon an armature lever 19 pivoted to a bearing 20 also in the said guide casing 15. This armature lever 19 is yieldingly retracted from the electro-magnet by a light coiled spring 21 attached to the lower end thereof, and to a projection of the bearing 20. When the indicator plate 16 is raised and the armature lever 19 is retracted, said plate will be held in such raised position by 15 the engagement of the upper end of said armature lever with a latch lug 22 on the said signal plate. Here it may be noted that the back of the guide casing 15 is cut away at 23 to afford clearance for movements of 20 the lugs 22 when the indicator plate 16 is raised and lowered.

On the back of the guide casing 15 is a 25 block 24 of insulating material to which is secured laterally spaced contact fingers 30 25, the free ends of which are in contact with the lug 22 (which latter is of metal) when the indicator plate is in its raised position. The electric circuits for energizing the magnet 18 may be the same, or substantially the same as those at present employed 35 for operating the signal bells, but in the drawings, Fig. 8, we have diagrammatically shown a signal circuit 26 connected to the said magnet and including a source of 40 energy 27, a push button 28 and the separated contacts 25. With this arrangement, as is evident, the magnets will be energized when, and only when the circuit is closed by engagement of the lug 22 with the contact 45 fingers 25, and by pressing together of the contact elements of the push button 28.

Normally, the indicator plate 16 will be 50 in its raised position shown in Fig. 5 and the word "Stop" on the said plate will be above the slot 14 so that a blank surface of the said indicator plate will be presented to the opening 14. When the magnet 18 is 55 energized, it will pull toward it the upper portion of the armature lever 19, thereby releasing the same from the lug 22 and permitting the indicator plate 16 to drop by gravity into the position shown in Figs. 3, 4 and 6, where it will present the word "Stop" in view of the opening 14.

60 When the said plate drops and the lug 22 moves out of engagement with the contact fingers 25, the magnet circuit will be broken and the magnet deenergized, so that no further current will be used until the signal 65 plate has been again raised and the push

button pressed. All that the magnet is called upon to do is to trip the signal plate and that requires but the slightest electrical impulses. If, after one person has given the stop signal, others press the same or 70 other push buttons, no further electrical or other actions will be produced and there will be no waste of current.

The indicator plate may be reset by hand when desired, but by a novel connection to 75 the gate actuating mechanism, it is arranged to be set automatically, or by an operation performed primarily for another purpose, to-wit, the opening and closing of the gates. This connection is preferably made as follows:

On the crank rod 10 of the gate actuating mechanism is a cam 29 that operates on the roller-equipped head 30 of the push rod 31, the end of which works telescopically in the 85 horizontal end portion of a guide tube 32, the lower portion of which is fixed to a suitable bearing 33 on the bracket 11, and the other end of which is vertically extended and attached to the bottom of the casing 13. 90 The elbow portion of this bent tube 32 is curved and is filled with small balls 34. Telescoped into the vertical upper portion of the guide tube 32 is a second push rod 35 that extends upward into the case 13 and 95 terminates in a head 36 that is adapted to engage the lower edge of the indicator plate 16. The rod 35 is yieldingly pressed downward, and the head of the lower rod 31 is yieldingly pressed against the cam 29, as 100 shown, by a coiled tension spring 37 anchored at its lower end to the bottom of the case 13 attached at its upper end to the upper end of the said push rod 35. The push rods 31 and 35 and interposed balls 34 afford a highly efficient flexible push rod 105 which will work with a minimum of friction. Normally, the head 36 of the push rod is lowered, as shown in Fig. 3, so that it affords a stop for limiting the downward 110 movement of the signal plate 16. When the crank rod 10 is oscillated to open and again close the gates, the cam 29, acting on the roller-equipped head 30 of the push rod, will raise the upper end head 36 thereof, and 115 cause the latter to again raise the said indicator plate to a position into which it will be latched by reengagement of the armature lever 19 with the lug 22, in which position, the said lug 22, of course, again makes the 120 electrical connection between the contact fingers 25 so that the circuits will be again closed whenever a push button is pressed.

In some instances, it is desirable to use a bell or audible auxiliary signal device in 125 connection with the visual signal device. In the drawings, a bell or gong 40 is attached within but to the back of the casing 13 and a clapper 41 is intermediately pivoted to the back of the casing just below the bell. 130

This clapper, at its long end, has a bell-engaging clapper head 42, and at its short end, has a laterally projecting finger 43 that will be engaged by the lower edge of the indicator plate 16 when the latter is dropped, as shown in Fig. 6. Thus, when the signal plate is dropped, one rap will be given to the bell. Attention is here called to the fact that in Fig. 3, the end of the finger 43 is broken off for clearness, but that it is, in fact, long enough to reach under the lower edge of the signal plate 16, so that it will be engaged, as shown in Fig. 6.

What we claim is:

- 15 1. The combination with a car having a gate and gate-actuating mechanism extended to and operative from a point remote from said gate, of a stop indicator, means for operating said stop indicator at will, and means for re-setting said stop indicator by operation of the extended gate actuating mechanism.
- 20 2. The combination with a car having a gate and a gate actuating mechanism extended to and operative from a point remote from said gate, of a visual indicator under strain to move in one direction, a latch for normally holding said indicator against movement, means operative, at will, to trip said latch and to release said indicator, and a resetting device operated by

gate operating movements of said extended gate actuating mechanism for restoring said indicator to normal position.

3. The combination with a car having a 35 gate and a gate actuating mechanism, of a visual indicator under strain to move in one direction, a latch for normally holding said indicator against movement, means operative, at will, to trip said latch and to release 40 said indicator, a resetting device operated by gate operating movements of said gate actuating mechanism for restoring said indicator to normal position, the said resetting device comprising a tube having straight 45 end and curved intermediate portions, rods working telescopically in the straight ends of said tube, balls in the curved portion of said tube between the inner ends of said push rods, and a cam operative on the end 50 of one of said push rods, and a cam connected to the said gate actuating mechanism and operative on the end of one of said push rods.

In testimony whereof we affix our signatures in presence of two witnesses.
